Charles M. Howard
By his Attorney
Sheffield & Ritter

UNITED STATES PATENT OFFICE.

CHARLES M. HOWARD, OF NEW YORK, N. Y., ASSIGNOR TO WINDSOR PRINT WORKS, OF NEW YORK, N. Y., A CORPORATION OF MASSACHUSETTS.

DESIGN FOR A PRINTED COTTON FABRIC.

47,517.

Specification for Design.

Patented June 29, 1915.

Application filed March 19, 1915. Serial No. 15,624. Term of patent 3½ years.

To all whom it may concern:

Be it known that I, CHARLES M. HOWARD, a citizen of the United States, residing in the borough of Manhattan, city, county, and State of New York, have invented a new, original, and ornamental Design for Printed Cotton Fabrics, of which the following is a specification, reference being had to the accompanying drawing, forming a part thereof.

The figure is a plan view of a portion of

a printed cotton fabric, illustrating my new design.

I claim:

The ornamental design for a printed cotton fabric, as shown.

CHAS. M. HOWARD.

Witnesses:

FRED'K G. HOWARD,
J. L. GEOFFROY.
